UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

COAL MINING METHOD AND APPARATUS

Application filed March 20, 1924, Serial No. 700,632. Renewed November 28, 1930.

The present invention relates to certain new and useful improvements in coal mining methods and apparatus, and particularly to a method and apparatus adapted to be used along the entire length of an elongated coal face to undercut the coal, or to undercut and then transport the dislodged coal longitudinally of the face.

Under some geological conditions coal may be efficiently recovered from its natural bed by the panel system of mining, in which parallel entries are first driven into the vein, and the intervening coal is afterwards removed from relatively long working faces extending between adjacent entries, the roof being allowed to subside behind the mining operations. Machines of various sorts, the active elements of which extend along the entire length of a mine face, have been provided for undercutting the coal and for transporting the dislodged coal longitudinally of the face to be loaded into receptacles suitably placed in the entries for its removal from the mine.

More particularly is the present development intended to provide a method and apparatus of cutting coal, which consists in first kerfing out a coal section, then dislodging the coal, and preferably, and, as here described, removing it by the same instrumentalities used to kerf it. It will be seen from the description of the method, and the operation of the apparatus designed to carry out that method, which follows, that a very efficient and economical system has been worked out for accomplishing this result.

It is the especial object of this invention to provide a coal cutting or coal conveying mechanism adapted to extend adjacent a relatively long coal face, and having both vertical and lateral flexibility whereby it may be adjusted to conform to irregularities in the contour of the mine floor or of the face of the vein.

A further object is to provide means to simultaneously impart uniform lateral motion to all parts of a flexible cutting and conveying mechanism, such as is above mentioned, to maintain it in working relation with the coal face.

A further object is to provide means to automatically adjust a mechanism of the class described to conform to the irregularities in the contour of the mine floor or of the face of the vein.

The means whereby I attain these objects are fully set forth in the following specification, reference being had to the accompanying drawings, of which—

Fig. 1 is a general plan view of a longwall coal cutting mechanism embodying my present invention.

Fig. 2 is an end elevation of the mechanism illustrated in Fig. 1.

Fig. 3 is a detail, on an enlarged scale, of the feeding devices illustrated in Fig. 1.

Fig. 4 is a section taken along the line IV—IV of Fig. 3.

Fig. 5 is a fragmentary view similar to Fig. 4, showing the adaptation of my improved coal cutting mechanism to the transportation of the dislodged coal longitudinally of the coal face.

Figs. 6, 7, 8, 9 and 10 are diagrammatic illustrations of the method of operating the machine.

Fig. 11 is a view similar to Fig. 2, showing means for effecting movement of the cutter chain at different speeds.

Fig. 12 is a detail of the cutter chain showing it equipped with a sweep or flight for gathering the material.

Fig. 13 is a view substantially on the line 13—13 of Fig. 12, looking in the direction of the arrows.

Fig. 14 is a detail perspective view of the pivot pin for securing the sweep to the chain.

In referring to the drawings, like numerals indicate similar parts in the several views.

For purposes of illustration, I have shown in the drawings an installation adapted to the recovery of a very thin vein of coal. As here illustrated, the numeral 1 indicates a panel or mass of coal lying between two parallel entries 2 and 3. The panel 1 has a working face 4 extending perpendicularly to said entries, and the length of this face depends upon the geological conditions existing in the mine. Owing to the extreme thinness of

55

the vein, it has been necessary to take up material from the mine floor, thus depressing the bottom of the entry 2, as shown at 5 in Figs. 9 and 10, to afford sufficient headroom 5 for the convenient operation of the pit cars 6 by which dislodged coal is transported from the mine. A bench 7 is retained along one side of the entry for the convenient handling of the power devices associated 10 with the mining mechanism, as will be more fully hereinafter described. The roof 8, adjacent the working face, may be supported in any preferred manner, as by a row of timber posts 9 positioned in the rear of the mining mechanism, which, as the face 4 recedes, 15 may, from time to time, be moved towards the coal face to allow the subsidence of the overlying strata. As these matters are well understood in the mining art, further description 20 of them is not thought to be required at this time.

Positioned adjacent the coal face 4 and extending along its entire length, is a frame 10, upon which the coal engaging mechanism is mounted. For purposes of illustration, I have here shown an undercutting mechanism adapted to form a kerf extending entirely across the face of the vein, but it is to be understood that other mechanism 25 adapted to perform other operations may be so mounted without departure from the spirit of my invention. The frame 10 is preferably composed of a plurality of cutter frame sections 10a, 10b, 10c, etc., arranged in longitudinal alignment, and each provided with a longitudinally extending lug 11 projecting into a recess of the adjacent section to which it is connected by a coupling pin 12. These parts are so proportioned 30 that the adjacent sections are connected together with a measure of flexibility both vertically and horizontally. Formed on the lateral edges of the sections 10a, 10b, 10c, etc. are guideways 13 in which travels the cutter chain 14 which is of the well known construction having laterally projecting renewable cutter bits 15 adapted to engage the coal to cut it. The guideways 13 of these sections will preferably be flared at their 35 ends, both laterally and vertically, as indicated in dotted lines at 13a, Fig. 3, so that as the sections flex relative to one another, as indicated in Figs. 8 and 9, where the outermost section is shown angularly disposed 40 with respect to the rest of the line, the cutter chain will travel smoothly past the adjacent ends of the sections 10a, 10b, 10c, etc. These cutter bits 15 also act to drag dislodged fragments of coal longitudinally of the coal face 4, and the last section 10a of the cutter frame projects beyond the edge of the bench 7 to discharge such loose material into a suitably positioned pit car 6. An apron 16, of any suitable material and construction, may be 45 placed between the edge of the bench 7, and

the side of the car 6, to conduct said loose material across the intervening space.

Formed on the outer end of the section 10a of the cutter frame is an upwardly projecting hub 17 in which is journaled the vertical head shaft 18 to which is attached the head sprocket wheel by which the cutter chain 14 is actuated in the manner well understood in the mining machine art. The hub 17 is rotatably mounted in a sleeve 19 formed on the rearward end of an arm 20 which is rigidly attached to the frame 21 of the power mechanism. The frame 21 rests directly upon the mine floor and is 50 slideable thereon, and these parts are so proportioned that a clear space is provided beneath the arm 20 and between the cutter frame 10 and power frame 21 for the passage of loose material to the pit cars 6. Mounted upon the frame 21 is a motor by 55 which the machine is actuated. This motor may be of any preferred type adapted to the conditions under which the machine is operated. For purposes of illustration, I have shown an electric motor 22 to the armature 60 shaft of which is attached a worm 23 which engages a suitable worm gear 24 fixed to the vertical shaft 25. The shaft 25 is journaled in suitable bearings of the power frame, and at its upper end is fixed a sprocket wheel 26 which is connected by a suitable endless chain 27 with the sprocket wheel 28 fixed to the head shaft 18 to actuate the cutter chain 14. Mounted upon the power frame 21 is a winding drum 29 which is connected by suitable gearing with the motor 22 and provided with suitable mechanism to control its actuation, for purposes which will 65 hereinafter appear. As the arrangement of such gearing is well understood in the mining machine art, and as it forms no part in the present invention, further description is not thought to be required at this time.

In order that the machine may be properly manipulated relative to the coal, I have provided a feeding mechanism comprising a rope 30 windable upon the drum 29 of the power mechanism, and adapted to cooperate with a plurality of anchor jacks 31 positioned outside of the machine, to uniformly move the cutter frame 10 laterally towards and from the coal face. Fixed to each section 10a, 10b, 10c, etc. of the cutter frame, and projecting perpendicular thereto, is an arm 32 shaped adjacent the cutter frame to form a sliding shoe 33 which engages the mine floor to support the cutter frame 10. The cutter frame 10 will preferably, as best shown in Figs. 4 and 5, be mounted on the end of the frame 32 adjacent the shoe 33 in an inclined position, so as to provide clearance for the bits 15, the shoe 33 being channeled, as shown, to receive the lower run of the bits. In this position of the cutter frame 10, it will be seen that the bits 15 at the rear of the frame will 70 75 80 85 90 95 100 105 110 115 120 125 130

cut in a higher plane than the bits at the front end of the frame 10 and form a clearance on the rear side of the frame for themselves and for the sheaves 42 and their associated parts. At its outer end there is provided a vertically extending adjusting screw 34 threaded in an aperture of the arm 32, and having at its upper end a hand wheel 35 for its convenient manipulation. At its lower end the screw 34 is provided with a floor engaging foot 36 adapted to sliding contact with the mine floor. By the adjustment of the screw 34 the arm 32 may be rocked about the sliding shoe 33 to effect vertical adjustment of the forward, or active, side of the cutter frame. Extending longitudinally of the arm 32 is a slot 37 through which extends the anchor jack 31 which is of the well known construction having a part 38 adapted to engage the mine floor, and a tubular part 39 telescoping therewith and adapted to engage the mine roof. The slot 37, as will be clear from a consideration of Fig. 3, provides a passage-way which permits forward and backward movement of the arm 32 and the cutter arms carried thereby, relative to the jack 31. The upper portion of the floor engaging part 38 is screw threaded, and to this part is fitted a hand wheel nut 40 by the adjustment of which the tubular part 39 may be forced against the mine roof to securely clamp the jack in position. A guide sheave 41 journaled upon the floor engaging parts 38 of the anchor jack, is positioned in substantially the same horizontal plane as other guide sheaves 42 and 43 which are mounted respectively at the inner and outer ends of the arm 32.

The rope 30, after passing around suitable guide sheaves 44, 45 and 46 of the power frame, is passed around the sheaves 42 and 43 of each successive arm 32 and engages the sheave 41 of each successive anchor jack 31, as illustrated in Figs. 3 and 6. When now the winding drum 29 is actuated to wind the rope 30, the shortening of the bights 47 and 58 at each anchor jack will move the cutter frame forwardly to cause the cutter bits 15 to engage the coal to cut it. In order that the cutter bits of the return strand of the chain 13 may clear the shoes 33, the cutter frame 10 may be inclined transversely of its length. However, the upper bits of the return strand, as has been stated, engage the coal at the top of the kerf to cut a sufficient clearance for the passage of the chain and to clear a sufficient space for the convenient operation of the fed rope 30 and its guide sheaves 42, as is clearly illustrated in Fig. 4 of the drawings. After the cutter frame has been advanced beneath the coal to the desired depth, the rope 30 will be readjusted about the sheaves 41 and 42, as illustrated in Fig. 7, by throwing the draft rope 30 off the sheaves 43 and reversing the loop on the anchor sheave 41, so that draft on the rope 30 from

the winding drum will cause the cutter frame to be moved toward the coal face in such manner that when the drum 29 is actuated, the cutter frame will be moved rearwardly and withdrawn from the kerf. After the coal has been thus undercut the coal above the kerf may be broken down in any preferred manner, as by the use of explosives, the feed rope 30 again adjusted about the sheaves 42, 43 and 41, as illustrated in Fig. 8, after which actuation of the cutter chain will cause the cutter bits 15 to engage the dislodging fragments of coal lying upon the mine floor and move them longitudinally of the face 4 over the apron 16 into the pit car 6. In order that, when the step of carrying out the coal, conventionally illustrated in Fig. 8 is being performed, the broken coal may be maintained in proper position to be engaged by the carrying out strand of the cutter chain and not work back over the rear of the frames, I provide a suitable shield 49 having supporting lugs 50 adapted to engage apertures 51 of the cutter frame; this shield may be adjusted, as illustrated in Fig. 5, to confine the dislodged coal to the forward side of the cutter frame.

In Figures 11 to 14, inclusive, I have shown my machine so equipped as that the cutter chain may be driven at different speeds. It is desirable to have the chain run faster when it is cutting, than when it is loading out the coal, for, in the latter operation, if the chain is driven at high speed, it sweeps through the dislodged coal and does not effectively carry it along.

The means for bringing about different speeds of the chain may, of course, be varied, but, as shown in Figure 11, I have accomplished it in the following manner. The construction is in all respects identical with that construction shown in Figure 2, except that the shafts 18 and 25 are extended, as shown in Figure 11, and a relatively large sprocket 52 is fixed on the shaft 18. Upon the extended shaft 25 a relatively small sprocket 53 is loosely mounted, the sprockets 52 and 53 being connected by a chain 54. The sprocket 55 in this form of the invention will be loosely mounted on the shaft 25, instead of fixed thereto, as in the form shown in Figure 2, and both the sprocket 53 and the sprocket 55 are provided with clutch surfaces, so that either one may be clutched to the shaft, any suitable clutch mechanism, 23 56, being provided.

While either of the chain and sprocket devices shown in Figure 11 may be the fast cutting drive, or the relatively slower conveying drive, I have here shown the upper sprockets 52 and 53 as the slow drive. The relatively small sprocket 53 will, when the clutch 56 engages it with the shaft, drive the sprocket 52 and the shaft 18, which operates the chain, at a slower speed, so that the cutter bits will not be swept through the material at such

speed that effective loading out of that material will not take place. When the sprocket wheel 55 of larger diameter is clutched to the shaft 25, the speed of the shaft 18 and the cutter chain will be increased, so as to give an effective cutting speed.

It may be desirable, in some circumstances, to relieve the long cutter chain of the weight of a large number of bits, and this can be done by omitting alternate bits, or alternate groups of cutter bits, in sufficient number to avoid overloading the apparatus. It sometimes happens, with some grades of coal, that the cutter bits do not effectively bring out the material, and in such case I provide, as shown in Figures 12 and 13, a sweep or flight 57 which may be attached to suitably formed links 58 of the chain. These flights may be arranged alternately with the bits, or in any desired grouping. The flights 57 may, of course, take different forms, and the manner of attaching them to the links 58 may be varied. I have here shown a flat flight 57 attached to a projecting lug on the link 58 by means of a pin 59, and that pin, as shown, is provided with a key 60 at one end designed to pass through key seats 61 in the lugs 62 of the flights 57, and the lug of the link 58. The pin 59 is also preferably provided at the end opposite the key with an offset weight, as 63, so that when the pin is inserted, the weight 63 will naturally fall to a pendant position, give a quarter turn to the pin, and bring the key 60 out of alignment with the key seat 61, as shown in Figure 13.

From the foregoing, it will be seen that by this method, and by means of the apparatus for carrying out the method, the steps of cutting, breaking down, and carrying out the broken down coal may be very readily carried on with the single apparatus, by simply adapting it to the different steps of the method. This eliminates the labor and time incident to the use of one apparatus for cutting the coal, and another apparatus for transporting or carrying out the broken down coal.

It will be seen also that the construction admits of adapting the cutter frame to various widths of coal face, for, by constructing the cutter frame of the assembled units, it may be set up in different lengths by simply adding to or removing units, thus giving a construction which may be conveniently adapted to panels of various widths.

As has been pointed out, the cutter frame is made up of sections 10a, 10b, etc., flexibly connected, so that, as indicated in Figures 8 and 9, they can adjust themselves to contours other than perfectly horizontal or vertical ones. For example, in Figure 8, it will be observed that the end unit 10f is out of alignment, and closer to the wall than the others, and in Figure 9 that same end frame has adapted itself to an irregular floor contour.

This frame construction admits of different manipulations of the cutter bar. It is possible to move all of the cutter bar sections simultaneously into the coal, or the sections may be advanced into the coal in irregular fashion, as shown in Figure 8. This might be desirable, particularly in loading out broken down coal. By pushing in the end section, as, for example, the section 10f, Figure 8, the coal at the bar end of the frame will be picked up first, and then, as succeeding sections were pushed in, the coal will be loaded out from the far end, gradually reducing the mass in length until it has been entirely removed.

Other manipulations of the flexible frame, to meet particular conditions, are, of course, possible, and properly within my invention.

I do not wish to be restricted to the precise construction and arrangement of parts here disclosed, since, while the embodiment of my invention which has been described and illustrated is primarily an undercutting mechanism adapted to be used in a secondary capacity as a conveyor, it is apparent that other coal working devices, such as conveyors of various sorts, may be constructed so as to fall within the spirit of my invention.

What I claim is:—

1. In a coal mining apparatus, the combination with an elongated frame adapted to rest upon and slide over the mine floor said frame comprising a plurality of longitudinally aligned flexibly connected sections, an endless chain adapted to travel in guideways extending longitudinally of said frame, cutter bits projecting laterally from said chain and adapted to engage the coal to cut it, means to actuate the chain, and means to simultaneously apply lateral moving effort to each of said sections as and for the purpose set forth.

2. In a coal mining apparatus, the combination with an elongated frame adapted to rest upon and slide over the floor of the mine said frame comprising a plurality of longitudinally aligned flexibly connected sections, an endless chain adapted to travel in guideways extending longitudinally of said frame, cutter bits projecting laterally from said chain and adapted to engage the coal to cut it, means to actuate the chain, and means actuated by the chain actuating means to simultaneously apply lateral moving effort to each of said frame sections as and for the purpose set forth.

3. In a coal mining apparatus, the combination with an elongated frame adapted to rest upon and slide over the floor of the mine, said frame comprising a plurality of longitudinally aligned flexibly connected sections, an endless chain adapted to travel in guideways extending longitudinally of said frame, cutter bits projecting laterally from said chain and adapted to engage the

coal to cut it, a motor mounted on one of the sections of said frame connected and arranged to actuate said cutter chain, and means actuated by said motor to simultaneously apply lateral moving effort to each of said frame sections as and for the purpose set forth.

4. In a coal mining apparatus, the combination with an elongated frame adapted to rest upon and slide over the floor of the mine, said frame comprising a plurality of longitudinally aligned flexibly connected sections, an endless flexible draft device adapted to travel in guideways extending longitudinally of said frame, material engaging elements carried by said draft device, means to actuate said draft device, and means to simultaneously apply lateral moving effort to each of said frame sections as and for the purpose set forth.

5. In a coal mining apparatus, the combination with an elongated frame adapted to rest upon and slide over the floor of the mine, said frame comprising a plurality of longitudinally aligned flexibly connected sections, an endless flexible draft device adapted to travel in guideways extending longitudinally of said frame, material engaging elements carried by said draft device, power devices upon said frame to actuate said draft device, and mechanism actuated by said power devices adapted to simultaneously apply lateral moving effort to each of said sections as and for the purpose set forth.

6. In a coal mining apparatus, the combination with an elongated frame adapted to rest upon and slide over the floor of the mine, said frame comprising a plurality of longitudinally aligned flexibly connected sections, of an endless flexible draft device adapted to travel in guideways extending longitudinally of said frame, material engaging elements carried by said draft device, power devices upon said frame to actuate said draft device, rope guiding devices upon each frame section, an abutment external of said frame adjacent each frame section, a rope adapted to engage said guiding devices and said abutments, and means to tension said rope to simultaneously apply lateral moving effort to each of said frame sections as and for the purpose set forth.

7. In a coal mining apparatus, the combination with an elongated frame adapted to rest upon and slide over the floor of the mine, said frame comprising a plurality of longitudinally aligned flexibly connected sections, a laterally projecting arm extending perpendicular to each section, an endless flexible draft device adapted to travel in guideways extending longitudinally of said frame, material engaging elements carried by said draft device, power devices upon said frame to actuate said draft device, a plurality of

rope guiding devices mounted upon said laterally projecting arms, an abutment external of said frame adjacent each of said arms, a rope adapted to engage the guiding devices upon the arms and the abutments, and means actuated by said power devices to tension said rope to simultaneously apply lateral moving effort to each of said frame sections as and for the purpose set forth.

8. In a coal mining apparatus, the combination with an elongated frame adapted to rest upon and slide over the floor of the mine, said frame comprising a plurality of longitudinally aligned flexibly connected sections, a laterally projecting arm extending perpendicular to each section, an endless flexible draft device adapted to travel in guideways extending longitudinally of said frame, material engaging elements carried by said draft device, a plurality of rope guiding devices mounted upon said laterally projecting arms, an abutment external of said frame adjacent each of said arms and engaging guideways thereof, a rope adapted to engage the guiding devices upon the arms and the abutments, and means actuated by said power devices to tension said rope to simultaneously apply lateral moving effort to each of said frame sections as and for the purpose set forth.

9. In a coal mining apparatus, the combination with an elongated frame comprising a plurality of longitudinally aligned flexibly connected sections, a laterally projecting arm extending perpendicular to each section, a shoe formed on each arm adapted to slidably engage the mine floor to support its frame section, an endless flexible draft device adapted to travel in guideways extending longitudinally of said frame, material engaging elements carried by said draft device, power devices upon said frame to actuate said draft device, and means actuated by said power devices and cooperating with said arms and an abutment adjacent each arm to simultaneously apply moving effort to each of said frame sections as and for the purpose set forth.

10. In a coal mining apparatus, the combination with an elongated frame comprising a plurality of longitudinally aligned flexibly connected sections each of which is provided with a supporting shoe slidably engaging the mine floor, longitudinally aligned guideways in said frame sections wherein travels an endless flexible draft device, and means to rock said frame sections upon their supporting shoes to effect the alignment of said guideways as and for the purpose set forth.

11. In a coal mining apparatus, the combination with an elongated frame comprising a plurality of longitudinally aligned flexibly connected sections each of which is provided with a supporting shoe slidably engaging the

mine floor, longitudinally aligned guideways in said frame sections wherein travels an endless flexible draft device, a laterally projecting arm extending perpendicular to each section, and means to vertically adjust the remote ends of said arms to effect the alignment of said guideways as and for the purpose set forth.

12. In a coal mining apparatus, the combination with an elongated frame comprising a plurality of longitudinally aligned flexibly connected sections each of which is provided with a supporting shoe slidably engaging the mine floor, longitudinally aligned guideways in said frame sections wherein travels an endless flexible draft device, a laterally projecting arm extending perpendicular to each section, an adjusting screw threaded in an aperture of each arm and adapted to engage the mine floor, and means to adjust said screw relative to said arm to effect the alignment of said guideways as and for the purpose set forth.

13. In an apparatus of the class described, the combination with an endless flexible draft device, of material engaging elements attached to said draft device, and a guiding and supporting frame adapted to cooperate with said draft device to cause the engagement of said elements with the material to be operated upon, said frame comprising a plurality of longitudinally aligned flexibly connected sections as and for the purpose set forth.

14. In an apparatus of the class described, the combination with an elongated frame composed of a plurality of longitudinally aligned flexibly connected sections, of means to simultaneously apply lateral moving effort to each of said sections as and for the purpose set forth.

15. In an apparatus of the class described, the combination with an elongated frame composed of a plurality of longitudinally aligned flexibly connected sections, adapted to flexure in either of two intersecting planes extending longitudinally of the frame, of means to simultaneously apply lateral moving effort to each of said sections as and for the purpose set forth.

16. In an apparatus of the class described, the combination of a cutter frame made up of a plurality of flexibly connected sections, a cutter chain carried by said flexible cutter frame, means for driving said chain, and means for moving the units of said flexible frame toward a coal face substantially at the same time.

17. In an apparatus of the class described, the combination of a cutter frame made up of a plurality of flexibly connected sections, a cutter chain carried by said cutter frame, means for driving said chain, and means associated with each unit of said flexible frame to move such units toward a coal face substantially at the same time.

18. In an apparatus of the class described, the combination of an elongated cutter frame, a cutter chain carried by said frame, means for driving said chain, a plurality of cable engaging devices extending rearwardly from said frame, and a cable engaging each of said devices to exert moving pressure upon the frame at a plurality of points throughout its length to advance or retract it relative to a coal face.

19. In an apparatus of the class described, the combination of an elongated cutter frame, a cutter chain carried thereby, means for driving said chain, a plurality of cable engaging devices extending rearwardly from said frame, a continuous cable extending substantially parallel to said frame and having laterally disposed loops engaged with said cable engaging devices, and means for exerting draft on said cable to effect movement of said frame toward or from a coal face.

20. In an apparatus of the class described, the combination of a cutter frame, a cutter chain carried thereby, means for driving said chain, rigidly disposed arms projecting rearwardly from said frame, cable engaging devices carried by said arms, a cable disposed substantially parallel to said frame and having loops extending laterally therefrom substantially in line with said arms, an anchor device for said loops, and means for exerting draft upon said cable to effect movement of said cutter frame.

21. In an apparatus of the class described, the combination of a cutter frame, a chain carried thereby, means for driving said chain, a plurality of arms extending from said frame and each having a longitudinally disposed slot, cable engaging devices carried by said arms, cable engaging anchors passing through the slots in said arms, a cable disposed substantially parallel to said frame having loops engaged with said cable engaging devices and said anchors, and means for exerting draft on said cable to move said frame.

22. In an apparatus of the class described, a cutter frame formed of a plurality of sections connected end to end for relative vertical and horizontal movement, a cutter carried by said frame, arms extending rearwardly from each of said units, cable engaging devices on said arms, cable engaging anchors, a cable disposed substantially parallel to said frame and having loops engaged with said cable engaging devices and said anchors, and means for exerting draft on said cable to move said frame.

23. In an apparatus of the class described, an inclined cutter frame formed of a plurality of sections connected end to end for relative vertical and horizontal movement, a cutter carried by said frame, arms extending rearwardly from each of said units, means for adjusting said arms vertically, cable en-

gaging devices on said arms, cable engaging anchors, a cable disposed substantially parallel to said frame and having loops engaged with said cable engaging devices and said anchors, and means for exerting draft on said cable to move said frame.

24. In an apparatus of the class described, the combination with a plurality of cutter frame supports adapted to rest upon and slide over the floor of a mine, an elongated cutter

10 frame mounted upon said supports and movable laterally therewith perpendicularly towards the coal face, a cutter chain adapted to travel in guideways along the lateral edges of said cutter frame to engage the coal to cut a kerf therein, and means for tilting said supports to so incline the cutter frame that the cutter chain on opposite sides of said frame shall travel in different horizontal planes as and for the purpose set forth.

20 25. In an apparatus of the class described, the combination with an elongated frame comprising a plurality of aligned flexibly connected sections, an endless chain adapted to travel in guideways formed in said frame sections, material engaging elements carried by said endless chain, means to drive said chain, and means to move the units of said flexible frame towards the material which is to be moved.

30 35. In an apparatus of the class described, the combination with a cutter frame support adapted to rest upon and slide over the floor of a mine, cutting mechanism carried by said frame adapted to engage the coal to form a kerf therein, cutting mechanism in the rear of the first mentioned cutting mechanism adapted to engage the coal above said kerf to widen said kerf, means to move said support to cause said cutting mechanism to engage the coal to cut it, and means to rock said cutting mechanisms about a substantially constant axis intermediate their paths.

40 45. In an apparatus of the class described, the combination of a cutter frame consisting of a plurality of flexibly connected sections, a cutter chain carried by said flexible cutter frame, and means for tilting each section of the frame independently of the others.

50 55. In an apparatus of the class described, the combination of a frame consisting of a plurality of flexibly connected sections, an endless draft element mounted upon said frames, material engaging elements carried by said draft element, and means for tilting each section transversely of its longitudinal axis.

59 60 65. In an apparatus of the class described, the combination of a frame consisting of a plurality of flexibly connected sections, an endless draft element mounted upon said frames, material engaging elements carried by said draft element, and screw means carried by each section for tilting each section transversely of its longitudinal axis.

30. In an apparatus of the class described, the combination of a frame consisting of a plurality of flexibly connected sections, an endless flexible draft device carried by said sections, material engaging elements carried by said draft device, each section having a laterally projecting arm, and means on the end of said arm for tilting each section.

31. In an apparatus of the class described, the combination of a cutter frame adapted to be arranged in a position inclined transversely of its longitudinal dimension, feeding means for moving said frame transversely, and a cutter chain mounted on said inclined frame with its cutter bits on opposite sides of the frame lying in different horizontal planes to cut a clearance for said feeding means.

32. In an apparatus of the class described, the combination of a plurality of frames 35 adapted to be assembled in an extended series, an endless flexible draft device mounted upon said frames, material engaging elements carried by said draft device, and means for connecting said frames together to permit relative angular movement thereof.

33. In an apparatus of the class described, the combination of a plurality of frames adapted to be assembled in an extended series, an endless flexible draft device mounted upon 45 said frames, material engaging elements carried by said draft device, and means for connecting said frames together to permit flexure thereof in either of two intersecting planes.

34. In an apparatus of the class described, the combination with a plurality of sections 50 adapted to be assembled in an extended series, the adjacent ends of adjacent sections being flexibly connected by a projection of one entering the recess of the other, and an endless 55 flexible draft device mounted upon said sections.

35. In a machine of the class described, an elongated base member composed of articulated sections, material-engaging elements 60 movable throughout said sections longitudinally thereof, said sections being movable in a lateral direction to conform to the outlines of a mass of material and to engage said elements therewith.

36. In a machine of the class described, an elongated base member composed of articulated sections, an endless draft device traversable along said sections, material-engaging elements on said draft device, said sections 70 being movable in a lateral direction to conform to the outlines of a mass of material and to engage said elements therewith.

37. In a machine of the class described, an elongated base member composed of articulated sections, material-engaging elements 75 movable throughout said sections longitudinally thereof, and means to apply lateral moving force to a selected section to engage respective elements with a mass of material.

38. In a machine of the class described, an elongated base member composed of articulated sections, material-engaging elements movable throughout said sections longitudinally thereof, and means to apply lateral moving force to selected sections to engage respective elements with a mass of material.

39. In a machine of the class described, an elongated base member composed of articulated sections, material-engaging elements movable throughout said sections longitudinally thereof, and means to apply lateral moving force to all of said sections to engage said elements with a mass of material.

40. The method of taking coal from a mine consisting in advancing a kerfing instrumentality into the base of a mine face to form a kerf therein, withdrawing said instrumentality, breaking down the kerfed material, and again advancing said instrumentality to drag out the broken down material and, in its continuing advance, to under kerf the succeeding increment.

41. The method of taking coal from a mine consisting in alternately advancing a kerfing instrumentality into a mine face and withdrawing it therefrom, each advance movement subsequent to a withdrawal being substantially twice the distance of the withdrawal movement, the coal being broken down prior to such subsequent advance movement, and said instrumentality in its advance removing the broken down material and then underkerfing the succeeding increment.

42. The method of taking coal from an extended mine face between two workings consisting in alternately advancing a kerfing instrumentality into the mine face throughout its length and withdrawing it therefrom, each advance movement subsequent to a withdrawal being substantially twice the distance of the withdrawal movement, the coal being broken down prior to such subsequent advance movement, and said instrumentality in its advance removing the broken down material and then under-kerfing the succeeding increment.

43. In an apparatus of the class described, the combination with a cutter frame support adapted to rest upon and slide over the floor of a mine, an elongated cutter frame mounted thereon and movable laterally therewith towards an extended coal face, a cutter chain adapted to travel in guideways formed on the lateral edges of said cutter frame and adapted to engage the coal to form a kerf therein, said cutter frame being so inclined that the cutter chain on opposite sides of said frame shall travel in different horizontal planes to cut a kerf of sufficient width to permit the free entrance of the frame support therein.

44. In an apparatus of the class described, the combination with a cutter frame support

adapted to rest upon and slide over the floor of a mine, an elongated cutter frame mounted thereon and movable laterally therewith towards an extended coal face, a cutter chain adapted to travel in guideways formed on the lateral edges of said cutter frame and adapted to engage the coal to form a kerf therein, and means for tilting said support to so incline said cutter frame that the cutter chain on opposite sides thereof shall travel in different horizontal planes to cut a kerf of sufficient width to permit the free entrance of the frame support therein, the central horizontal plane of the kerf remaining substantially constant at various inclinations of said frame.

45. In an apparatus of the class described, the combination with a plurality of cutter frame supports adapted to rest upon and slide over the floor of a mine, an elongated cutter frame mounted on said supports and movable laterally therewith towards an extended coal face, a cutter chain adapted to travel in guideways formed on the lateral edges of said cutter frame and adapted to engage the coal to form a kerf therein, and means for tilting said supports to tilt said cutter frame about an axis substantially adjacent the longitudinal axis of the frame that the cutter chain on opposite sides thereof shall travel in different horizontal planes to cut a kerf of sufficient width to permit the free entrance of the frame support therein.

46. In an apparatus of the class described, the combination with a plurality of cutter frame supports adapted to rest upon and slide over the floor of the mine, an elongated cutter frame mounted upon said supports and movable laterally therewith perpendicularly towards the coal face, a cutter chain adapted to travel in guideways along the lateral edges of said cutter frame to engage the coal to cut a kerf therein, said frame being so inclined to the horizontal that the cutter chain on opposite sides of said frame shall travel in different horizontal planes to cut a kerf of sufficient width to permit the free entrance of the frame support therein.

In testimony whereof I have hereunto set my hand.

NILS D. LEVIN.
